UNITED STATES PATENT OFFICE

EVELYN E. VAUGHT, OF SAN DIEGO, CALIFORNIA

DESIGN FOR DRESSED RABBIT DOLL

Application filed January 7, 1929. Serial No. 29,523. Term of patent 7 years.

To all whom it may concern:

Be it known that I, EVELYN E. VAUGHT, a citizen of the United States, residing at San Diego, in the county of San Diego and State of California, have invented a new, original, and ornamental Design for Dressed Rabbit Doll, of which the following is a specification, reference being had to the accompanying drawing, forming a part thereof,

I claim:

The ornamental design for dressed rabbit doll, substantially as shown.

In testimony whereof, I have hereunto set my hand at San Diego, California, this 27th day of December, 1928.

EVELYN E. VAUGHT.
